(57) **CLAIM**

The ornamental design for a projection screen, as shown and described.

DESCRIPTION

FIG. 1 is a front perspective view of the projection screen showing a new design;

FIG. 2 is a back perspective view of the projection screen showing a new design;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is an enlarged perspective view of a portion of the projection screen within the area identified by broken circle "9" in FIG. 2;

FIG. 10 is an enlarged perspective view of a portion of the projection screen within the area identified by broken circle "10" in FIG. 5; and,

FIG. 11 is an enlarged perspective view of a portion of the projection screen within the area identified by broken circle "11" in FIG. 5.

The broken lines shown in the drawings FIGS. 1-4, and 9 are included for the purpose of illustrating stitching of the projection screen and form part of the claimed design. The dot dash lines represent a boundary for the purposes of disclosing areas of enlargement and form no part of the claimed design.

1 Claim, 11 Drawing Sheets
